FENDER FOR AN AUTOMOBILE

Homer C. La Gassey, Jr., Royal Oak, Mich., assignor
to Chrysler Corporation, Highland Park, Mich., a cor-
poration of Delaware

Filed Aug. 14, 1959, Ser. No. 57,189

Term of patent 7 years

(Cl. D14—6)

Fig. 1 is a side elevational view of a fender for an automobile showing my new design;

Fig. 2 is a top plan view thereof;

Fig. 3 is a rear elevational view taken on the line 3-3 of Fig. 1; and

Figs. 4, 5 and 6 are sectional views taken on the lines 4-4, 5-5 and 6-6 of Fig. 1.

The dominant features of my design reside in the full line portions of the drawing.

I claim:

The ornamental design for a fender for an automobile, substantially as shown and described.
